UNITED STATES PATENT OFFICE

PATRICK H. DONOVAN, OF CHICAGO, ILLINOIS, ASSIGNOR TO THE WESTINGHOUSE AIR BRAKE COMPANY, OF WILMERDING, PENNSYLVANIA, A CORPORATION OF PENNSYLVANIA

FLUID PRESSURE WATER SYSTEM

Application filed May 24, 1930. Serial No. 455,411.

This invention relates to fluid pressure water systems of the type used on railway cars and the like.

An object of the invention is to provide an improved fluid pressure water system for railway cars and the like.

Another object of the invention is to provide a fluid pressure water system of the above type in which improved means are provided for controlling the supply of air and water to the water reservoir.

Another object of the invention is to provide a fluid pressure water system of the above type in which an improved manually operated valve device is provided for controlling the air and water conduits leading to the water reservoir.

Another object of the invention is to provide a fluid pressure water system of the above type in which two sets of combination valve devices are employed, the first combination valve device having means for governing the air supply and means for reducing the air pressure and the second combination valve device having means for controlling the air supply and means for controlling the conduit through which water is supplied to the water reservoir, both of said controlling means being operated from a single shaft, so that when the air supply control means is operated to cut off the air supply to the water reservoir, the water supply control means is simultaneously operated to open the water supply conduit.

Another object of the invention is to provide an improved fluid pressure water system of the character mentioned which is simple in construction, and reliable and exact in function under all conditions of service.

The invention also comprises certain new and useful improvements in the construction, arrangement, and combination of the several parts of which it is composed, as will be hereinafter more fully described and claimed.

In the accompanying drawing; Figure 1 is a diagrammatic view, mostly in section, of a fluid pressure water system embodying the invention; Fig. 2 is an end view of a portion of the water filling valve operating mechanism, as seen from the line 2-2 of Fig. 1;

and Fig. 3 is a diagrammatic section of a modified form of water filling valve device.

Referring to the drawing, the equipment may comprise a water storage tank or reservoir 6, water filling valve device 7, a source 55 of compressed air, such as a reservoir 8, means for controlling the supply of compressed air from the source of supply to the water storage tank comprising a governor valve device 9 and a reducing valve device 60 10, and a second source of compressed air, such as a supplemental reservoir 11.

The reservoir 8 may be one of the reservoirs of the brake system on the car, such for instance, as the auxiliary reservoir, service reservoir, or emergency reservoir, since either one of these reservoirs is adapted to be kept supplied with compressed air from an air compressor on one of the vehicles of the train. The reservoir 11 is adapted to be 65 supplied with compressed air from the reservoir 8, and the air in the reservoir 11 is maintained at substantially the same pressure as is the maximum pressure of the compressed air in the reservoir 8, as long as the 70 car is coupled to the vehicle of the train having the air compressor. The purpose of the reservoir 11 is to provide means for supplying compressed air to the water reservoir 6, when the car is uncoupled from a vehicle 75 having an air compressor, or when the air pressure in the reservoir 8 fails from any cause, such as a broken train pipe.

Preferably, the governor valve device 9 and the reducing valve device 10 are 80 constructed as a single unit comprising a casing 85 also provided with a chamber 12, containing a strainer 13 for filtering the air passing through said valve devices.

The chamber 12, on the exterior of the 90 strainer 13 is connected to the reservoir 8, through a pipe 14. A portion of the chamber 12 is reduced so as to snugly fit the body of the strainer, and above the strainer 13, the casing is formed with a chamber 15. 95 Above the chamber 15, the casing is provided with a screw-threaded cap or plug 16, so that the strainer 13 can be easily removed for cleaning or replacement.

The governor valve device comprises a 100

valve piston 17 having a chamber 18 at one side connected to a passage 19 leading to the chamber 15.

The valve piston 17 is adapted in its down position to engage a seat or gasket 20 and is urged to this position by an expansible coil spring 21. The side of the valve piston 17 facing the seat 20 is provided with a seat rib 22 of less diameter than the diameter of the valve piston. The opposite side of the valve piston is provided with a seat rib adapted in the up position of the valve piston to engage a seat or gasket 23 mounted in a chamber 24. The seat 23 is carried by a plate 25 having screw-threaded engagement with the wall of the chamber 24, so that the relative position of the seat 23 can be adjusted to the desired position for limiting the up movement of the valve piston.

The reducing valve device 10 comprises a diaphragm 26, which is mounted in the casting between chambers 27 and 28, the chamber 27 being connected to the atmosphere, through a port 29.

The diaphragm 26 carries a poppet valve 30 which is disposed in a chamber 31 separated from the chamber 28 by a wall 32, the valve 30 being connected to the diaphragm 26 by a fluted stem 33 passed through an opening or bore 34 in the wall 32.

On one side the diaphragm 26 is subject to the pressure of a spring 35 contained in chamber 27, and on the opposite side the diaphragm is subject to the pressure of fluid admitted to the chamber 28 through the opening 34 when the valve 30 is unseated.

The valve 30 is provided with a seat face adapted to engage a seat rib 36, so as to cut off communication through the opening 34 from the chamber 31 to the chamber 28, and said valve is urged against said seat rib by an expansible coil spring 37 contained in chamber 31.

Chamber 31 is connected to the chamber 18, through a passage 38 provided with a ball check valve 39 adapted to prevent back flow from the chamber 31.

The water filling valve device 7 comprises a casing provided with valve means for controlling the supply of water to the reservoir 6, and valve means for controlling the supply of air to said reservoir.

In the form of the water filling valve device 7 shown in Fig. 1, two tappet valves 40 and 41 are provided, one for controlling the air supply and the other for controlling the water supply.

The valve 40 is contained in a chamber 42, which is provided with an upwardly extending open neck 43 in which is adapted to be inserted a water hose, or the like, leading from a suitable source of water supply.

The valve 40 is adapted to control the communication from the chamber 42 to the water reservoir 6, provided by a passage and pipe

44, and said valve is normally held seated against a seat rib 45 at the inner end of the passage 44 by a spring 46 contained in chamber 42.

The valve 41 is contained in a chamber 47, which is open to the atmosphere through a vent port 48.

Contained in a chamber 50, is a poppet valve 49, which is connected to the valve 41 by a fluted stem 51. The fluted stem 51 passes through an opening 52 formed in the wall separating the chamber 50 from the chamber 53 on the side of the valve 41 opposite to the chamber 47. Chamber 53 is connected to the water reservoir 6, through a pipe 54, and chamber 50 is connected to the chamber 28, through a pipe and passage 55, a ball check valve 56 being provided in the passage 55 so as to prevent back flow from the chamber 50.

The valve 41 is normally adapted to engage a seat rib 57, so as to cut off communication from the chamber 53 to the atmospheric vent port 48, and said valve is urged toward said seat rib by a spring 58 contained in chamber 47.

The valves 40 and 41 are adapted to be manually operated, and for this purpose any suitable mechanism may be provided. In the present instance, the stem of the valve 40 is connected by a link 59 to a crank arm 60, fixed to a shaft 61, and the stem of the valve 41 is connected by a link 62 to a similar crank arm 63 fixed to said shaft.

The shaft 61 is journalled in suitable bearings 64 which may be attached to the under side of the car (not shown), and at one end the shaft is provided with a lever 65, which is held in two positions by a pawl 66. For this purpose, the lever 65 is provided with recesses 67 for receiving a projection or tongue 68, formed on the pawl 66.

In operation, the lever 65 is normally in the position shown in Figs. 1 and 2 in which position the valve 40 is seated by the pressure of spring 46 and the valve 49 is unseated and valve 41 seated by the spring 58, and it is assumed that the reservoir 6 is filled with water in the manner to be hereinafter described.

The fluid pressure brake equipment on the car, including the reservoir 8, is charged with air under pressure in the usual well known manner, and air under pressure flows from the reservoir 8 through pipe 14, strainer 13, chamber 15 and passage 19, to the chamber within the seat rib 22 of the valve piston 17. When the pressure in the reservoir 8 and thus acting on the valve piston 17, becomes sufficient to overbalance the opposing pressure of spring 21, the valve piston 17 is moved upwardly. Upon disengagement of the seat rib 22 of said valve piston from the seat 20, the whole lower surface of said valve piston is exposed to the pressure of air from

reservoir 8, and this increase in pressure on said valve piston quickly moves the valve piston into engagement with the gasket 28.

With the valve piston 17 thus seated in its upper position, air under pressure is permitted to flow from passage 19, through chamber 18 and past ball check valve 39, to valve chamber 31 of the reducing valve device 10, and from thence, through passage 10 and pipe 70 to the reservoir 11.

With diaphragm chamber 28 of the reducing valve device 10 initially uncharged, the pressure of spring 35 deflects the diaphragm 26 downwardly and the valve 30 is consequently unseated. Air under pressure is thereby permitted to flow from valve chamber 31 to the water reservoir 6, by way of unseated valve 30, diaphragm chamber 28, passage 55, past the ball check valve 56, pipe 20 55, past the unseated valve 49 in chamber 50, and from thence, through opening 52, chamber 53, and pipe 54.

When the pressure thus supplied to the diaphragm chamber 28 and water reservoir 25 6 becomes sufficient to over balance the opposing pressure of spring 35 on diaphragm 26, said diaphragm is deflected upwardly, permitting spring 37 to seat valve 30 and prevent a further pressure increase in the reservoir 6 and chamber 28.

It should be noted that the air supplied to the supplemental reservoir 11 is at substantially the same pressure as the pressure of the air in reservoir 8. However, should the pressure of the air in reservoir 8 be decreased from any cause, the ball check valve 39 will prevent a corresponding decrease in the pressure of the air in the reservoir 11, so that even though the supply of air from the reservoir 30 8 be cut off through loss in pressure by the valve piston 17, the pressure of the air in chamber 31 will be maintained by the air in reservoir 11.

The air under pressure supplied through the pipe 54 to the water reservoir 6 forces the water through the pipe 71 into the car, where the water is distributed to the various fixtures. (not shown).

When water is withdrawn from the reservoir 6, the air pressure reduces, and this causes a corresponding reduction in the pressure in chamber 28 of the reducing valve device 10, so that the diaphragm 26 is deflected downwardly by the pressure of spring 35. This action unseats valve 30 and thereby permits air under pressure to flow from the valve chamber 31 to the water reservoir 6 and recharge said reservoir in the manner above described.

When the supply of water in the reservoir 6 is depleted, and it is desired to refill the same, the operator lifts the pawl 66 of the water filling valve device 7 and moves the lever 65 downwardly from the position shown in Figs. 1 and 2, to a substantially vertical

position in which the projection 68 on the pawl 66 engages the other notch 67 and locks the lever.

The movement of the lever 65 rotates the shaft 61 in a counter clockwise direction, and 70 the valves 40 and 41 are thereby moved outwardly from their respective seat ribs, compressing the springs 46 and 58 respectively.

In the outward movement of the valve 41, the valve 49 attached thereto by the stem 73 51, is moved into engagement with the seat rib 69, thereby cutting off the supply of compressed air to the reservoir 6. At the same time, the valve 41 uncovers the vent port 48, so that the compressed air in the reservoir 6 20 is vented to the atmosphere.

With the valve 40 unseated from the seat rib 45, a communication is established through which water can be supplied to the reservoir 6 from the filling opening through 25 passage and pipe 44. The end of a hose (not shown), leading from a suitable source of water supply, can now be inserted in the neck 43 and the reservoir 6 filled with water, after which the lever 65 is operated to return the parts to their respective positions, as shown in the drawing, whereupon the air under pressure will be supplied to the reservoir 6 in the manner above described.

In lieu of the type of water filling valve 30 device 7 shown in Fig. 1, another type of valve device may be utilized, such for instance as the type shown in Fig. 3, in which a ball check valve 72 is provided. In this form of the invention, operating mechanism 100 is only required for controlling the air pressure controlling valves 41 and 49, since the ball check valve 72 is adapted to automatically control the communication from the filling neck 43 to the pipe 44 and prevent back flow 105 of the water from the reservoir 6.

While two illustrative embodiments of the invention have been described in detail, it is not my intention to limit their scope to these embodiments or otherwise than by the terms of the appended claims.

Having now described my invention, what I claim as new and desire to secure by Letters Patent, is:

1. A fluid pressure water supply system 110 comprising a water reservoir, a source of air under pressure, a supplemental air reservoir, a governor valve device for automatically interrupting communication between said source and said water and air reservoirs when the pressure of the air in said source decreases a predetermined amount, a reducing valve device for automatically controlling communication between both said sources and said supplemental air reservoir and said water reservoir, and a manually operable valve device for selectively establishing communication between both said source of air under pressure and said supplemental air reservoir, and said water reservoir, between 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990

said water reservoir and atmosphere and between said water reservoir and a source of water supply.

2. In a fluid pressure water supply system, the combination of two reservoirs normally charged with fluid under pressure, of another reservoir containing water and normally subject to the pressure of fluid from said first mentioned reservoirs, means operative upon a reduction in the pressure in the last mentioned reservoir for supplying fluid under pressure from said first mentioned reservoirs to said last mentioned reservoir, and means subject to the pressure of fluid in one of said first mentioned reservoirs for controlling communication between such reservoir and the other of said first mentioned reservoirs.

3. In a fluid pressure water supply system, the combination of a storage reservoir normally charged with fluid under pressure and an additional reservoir adapted to be charged from the storage reservoir, of a water reservoir containing water and normally subject to the pressure of fluid supplied from said additional reservoir, means operative upon a reduction in the pressure in said water reservoir for supplying fluid under pressure from said additional reservoir to said water reservoir, and a check valve for controlling communication between said additional reservoir and said storage reservoir and adapted to prevent back flow from the additional reservoir to the storage reservoir.

35 In testimony whereof I have hereunto set my hand, this 19th day of May, 1930.

PATRICK H. DONOVAN.
